 Filed May 27, 1968, Ser. No. 32,223
 2 Claims. (Cl. 317—262)

This invention relates to the treatment of a moving web of material and more particularly to a method of and apparatus for applying an electrostatic charge to the surface of a moving web of non-conducting material.

It is well known in the art to utilize corona discharge devices for applying an electrostatic charge to web and sheet material. In practice an ionized zone is established between a grounded metal backplate and the discharge devices, and the sheets to be charged are positioned in the ionized zone for a short period of time. When a moving web of material is electrostatically charged as it passes through such a zone the electrostatic attraction which occurs between the web and the backplate causes the web to frequently contact the backplate, thus producing an irregular friction drag on the moving web. It is quite difficult, therefore, to maintain a uniform tension in the web or a uniform feed thereof. With the method and apparatus of the present invention, these disadvantages of the known apparatus as regards to a moving web are avoided. Broadly, the present invention involves the establishing of an ionized zone adjacent to the periphery of a grounded electrically conducting roller, and moving the web through the ionized zone in spaced relation to the periphery of the roller. More specifically the present invention contemplates the use of such a roller as a guide for the web and as a grounded backplate for the corona discharge device.

The primary object of the present invention is, therefore, to provide an improved apparatus for applying an electrostatic charge to the surface of a moving web of non-conducting material.

Another object of the present invention is to provide a novel method of electrostatically charging a moving web of nonconducting material.

Still another object of the present invention is to provide an apparatus for electrostatically charging a moving web of non-conducting material which does no adversely affect the uniformity of feed and tension in the moving web.

Yet another object of the present invention is to provide an apparatus for electrostatically charging a moving web of non-conducting material in which an ionized zone, through which the web is advanced to receive an electrostatic charge, is established adjacent to the periphery of a grounded electrically conducting roller over which the web is passed, thereby eliminating the need for a stationary backplate.

Still another object of the present invention is to provide a relatively simple apparatus for and method of electrostatically charging a moving web of non-conducting material which is efficient and relatively inexpensive to use.

Still other objects and advantages of the present invention will become readily apparent to those skilled in the art from the following description with reference to the drawing in which like characters denote like parts and wherein:

FIG. 1 is a schematic view illustrating the preferred embodiment of the present invention; and

FIG. 2 illustrates another embodiment of the present invention.

In FIG. 1 the character W designates a web of non-conducting material, such as, for example, paper, card-

2

board, plastic, etc., which is drawn in the direction of the arrow from a supply thereof (not shown) over the periphery of a grounded metal roller 11 by means of feed rollers 13 and 15. Electrically non-conductive feed rollers 13 and 15 are driven in synchronism by means of an electric motor 17 and a suitable belt drive 19. In order to facilitate the clarity of the drawing, the mechanism by which the feed rollers 13 and 15 are connected for synchronous movement is not shown. Metal roller 11 is grounded as indicated at 21. A corona discharge device of the type well known in the art, with its projecting needle 23 is mounted in fixed relation in the apparatus with the needle extending preferably along a line which intersects the rotational axis of roller 11. The tip of needle 23 is spaced from the periphery of roller 11 by a distance designated by the character B. The web W after leaving the periphery of roller 11 is passed through a zone of ionized air which is maintained between the needle 23 and ground when the corona discharge device is connected to a suitable unidirectional high voltage supply (not shown). This zone is schematically illustrated in the drawing by the dashed lines extending between the periphery of the roller and the tip of needle 23. When passing through the zone web W is spaced from the periphery of the roller 11 by a distance designated by the character A. The dots placed adjacent to the surface of web W in the drawing are intended to indicate the presence of electrostatic charges which have been deposited on the web as a result of passing through the ionized zone.

Obviously the specific voltage which is required in any particular installation and the specific distances A and B which provide optimum charging efficiency will vary depending upon the physical and electrical characteristics of the web which is to be charged and atmospheric conditions. We have found in one installation of apparatus of the type illustrated in FIG. 1, that a D.C. potential of approximately 3600 to 12,000 volts applied between the needles and the grounded roller resulted in a charge equivalent to a web potential of approximately 1500 to 19,000 volts as measured by an electrostatic field meter or "field-mill" as it is known in the art, to a paper web approximately 70 mm. wide and 0.075 mm. thick. In that installation the distance A was approximately 11 mm. and B approximately 37 mm. The resistivity of the paper web was approximately 1×10^{10} ohms-cm. Changing the spacing of the web and corona discharge device so that A—from 5 mm. to 25 mm. and B—from 8 mm. to 50 mm. does not decrease the efficiency of the apparatus by more than 20%. In the apparatus a corona discharge device having two spaced needles was utilized in order to fully cover the 70 mm. width of the paper, but if a different width web is to be charged the number of needles should be varied accordingly.

The fact that any grounded metal roller over which a non-conducting web normally passes can function as a backplate during application of an electrostatic charge to the moving web is unexpected, since it would be thought that any electrostatic charge picked up by the web would tend to leak off to the grounded electrically conducting roller. This does not occur, however, even with a relatively poor insulator such as paper. It is possible to use such a roller as a contact backplate, as used in charging materials in sheet form, or as a backplate spaced at various distances from a moving web of material. In FIG. 2 the grounded metal roller 111 acts as a contact backplate for web W. The needle 123 of the corona discharge device is mounted opposite the arc of contact of web W with roller 111. In this instance the D.C. potential between the needle 123 and ground is kept between 3000—5000 volts. If greater potentials are utilized, dis-

charges are apt to occur between web W and roller 111 as the web is drawn away from the periphery of the roller. Again it should be realized that the exact potentials utilized may vary slightly depending upon the material of web W.

It will now be appreciated by those skilled in the art that we have disclosed a novel method and apparatus for electrostatically charging a moving web of non-conducting material. It is realized that many modifications and variations of the embodiments specifically described herein are possible. For example, it is also possible to place the needles of the corona discharge device 25 mm. from the roller at the point of separation of the web from the periphery of the roller and still obtain satisfactory results. In that instance lower potentials for the corona discharge device are required in order to provide the same amount of electrostatic charge on the web as is obtained with the preferred embodiment described herein. However, the ability to charge to various potential levels is lost. In view of this variation and the other modifications and variations which will become readily apparent to those skilled in the art from the foregoing description, the description is intended to be illustrative only and the scope of the invention is defined in the appended claims.

Having now particularly described our invention, what we desire to secure by Letters Patent of the United States and what we claim is:

1. In an apparatus for depositing an electrostatic charge on a web of nonconducting material, a roller mounted for rotation about an axis for guiding said web, said roller being comprised of an electrically conductive material and being electrically grounded, a corona discharge device

in spaced relation with respect to said grounded roller, said corona discharge device being operatively associated with said roller and being so located with respect thereto as to maintain an ionized zone between said device and a first portion of the periphery of said roller, means for moving said web about said roller in surface contact with a second peripheral surface portion of said roller independent of said first surface portion and for moving said web between said roller and said corona discharge device, said second peripheral portion comprising all of the surface of the roller in contact with the web, whereby said web is passed through said ionized zone for deposition of an electrostatic charge thereon, and whereby the relative spacings of said web and said corona discharge device from said roller may be varied to achieve optimum charging efficiency.

2. Apparatus according to claim 1 wherein said corona discharge device is located such that said web is moved through said ionized zone after leaving said second peripheral portion of said roller.
